UNITED STATES PATENT OFFICE.

LUTHER M. FISHER, OF ROCKY MOUNT, VIRGINIA.

OIL-TEST COCK.

1,368,329.

Specification of Letters Patent. Patented Feb. 15, 1921.

Application filed May 3, 1920. Serial No. 378,556.

To all whom it may concern:

Be it known that I, LUTHER M. FISHER, a citizen of the United States, residing at Rockymount, in the county of Franklin and State of Virginia, have invented certain new and useful Improvements in Oil-Test Cocks, of which the following is a specification, reference being had to the accompanying drawings.

10 This invention relates to an improved oil test cock particularly adapted for use in connection with a crank casing of combustion engines of automobiles especially of the Ford type, and an object is to provide a device of this kind, wherein simple, efficient, novel and practical features of construction are involved, and wherein the valve of the cock is automatically closed after opening the valve to test the level of the oil in the 20 crank case. In other words, with an oil test cock of this type, the oil cannot escape from the crank case unknowingly, for when the valve of the cock is open, means is afforded for automatically closing.

25 Another object is to provide a device of this character, wherein there is no way of forgetting to leave the valve open.

Heretofore a chauffeur when testing the 30 level of the oil in the crank case leaves the tap or valve open. Again the tap is sometimes turned or opened by a piece of brush or stick in the roadway. In either case the oil leaks from the crank case and damage will undoubtedly follow, therefore, a further 35 object is to avoid these disadvantages or inconveniences and to provide a very simple, and efficient valve cock, which will automatically close after it has been once opened and the level of the oil tested.

40 While the design and construction at present illustrated and set forth is deemed preferable, it is obvious that as a result of a reduction of the invention to a more practical form for commercial purposes, the invention 45 may be susceptible to changes, and the right to these changes is claimed, provided they are comprehended within the scope of what is claimed.

The invention comprises further features 50 and combination of parts, as will be herein-after set forth, shown in the drawings and claimed.

In the drawings:

Figure 1 is a view showing the improved oil test cock as applied. 55

Fig. 2 is a sectional view through the same, showing the construction of the valve cock.

Fig. 3 is a cross sectional view on line 3-3 of Fig. 1. 60

Fig. 4 is a detail view of the lever 18; and

Fig. 5 is a detail perspective view of the valve 8 and its stem.

Referring to the drawings, 1 designates a 65 crank case of a conventional form of internal combustion motor and 2 denotes the oil test cock casing, which is threaded at 3 into the wall of the crank casing, and is provided with a chamber 4. This chamber 70 has an opening 5 through the threaded part of the casing, communicating with the crank casing of the motor. The chamber 4 has a lateral opening 6 through which the level of the oil in the crank casing can be ascertained. The opening 5 has a valve seat 7 which is engaged by a valve 8 to prevent the escape of the oil from the crank casing. The valve 8 has a stem 9 which passes through the chamber 4, and is guided 80 through a bushing 10, which is mounted in the chamber 4. Interposed between the bushing and the valve 8 in surrounding relation to the stem is a coil spring 11 acting to normally hold the valve 8 in engagement 85 with its seat. The bushing 10 has a groove 12 extending perpendicular to its axis. This groove when the bushing is in proper place registers with an opening 13 extending through one corner of the casing 2 so that 90 the opening 13 and the groove 12 may receive a suitable cotter pin 14 thereby holding the bushing in position to hold the spring in place. Extending from the casing 2 is a pair of spaced arms 15 provided 95 with openings 16. A cotter pin 17 engages through the openings 16 of the arms 15 and through a lever 18 thereby pivotally mounting the lever between the arms. This lever 18 has a finger piece 19 so that it may be 100 engaged by the finger and tilted upon its pivot. The other end of the lever has a cam edge 20 so as to coöperate with one end 21 of the slot 22 of the stem of the

valve. It will be noted that by applying pressure on the finger piece end of the lever, the lever may be tilted and movement imparted to the stem, thereby unseating the valve, permitting the elevation of the oil in the crank casing to be ascertained through the lateral opening of the casing 2.

The invention having been set forth, what is claimed as new and useful is:—

- 10 1. A test cock comprising an integral casting adapted to be threaded into a crank casing and provided with a valve chamber having a valve seat at one end adjacent the crank casing, a valve normally engaging said seat to control communication with the crank casing and provided with a valve stem, a guide bushing in the opposite end of said chamber for the reception of said stem, a spring interposed between the valve 20 and the guide bushing, the end of the stem

beyond the bushing having a slot, said integral casing having an extension, a cam lever pivotally mounted on the extension and operatively engaging said slot, whereby upon tilting the lever, the valve may be 25 unseated against the action of the spring.

2. A valve comprising a casing having a valve seat at one end, a tensioned valve mounted in the casing and adapted to cooperate with the seat and provided with a 30 stem, a guide bushing in the other end of the casing for the stem, said bushing having a groove, and a cotter pin passing through one corner of the valve casing and engaging the groove in the bushing to retain the latter in position.

In testimony whereof I hereunto affix my signature.

LUTHER M. FISHER.
